CARBURETER.

1,391,025.

Specification of Letters Patent. Patented Sept. 20, 1921.

Application filed April 23, 1917. Serial No. 163,770.

To all whom it may concern:

Be it known that we, JAMES J. TRACY and LAWRENCE H. MORSE, both citizens of the United States, and residents of Cleveland, county of Cuyahoga, and State of Ohio, respectively, have jointly invented a new and useful Improvement in Carbureters, of which the following is a specification; the principle of the invention being herein explained and the best mode in which we have contemplated applying that principle, so as to distinguish it from other inventions.

The present improvements, relating as indicated to carbureters, have as their object the provision of a carbureter wherein the air friction, or flow of air drawn through the device by the suction of the engine, will serve to open and regulate, not only such flow of air, but also the flow of the hydrocarbon fuel, which is mixed therewith to form the charge proper. A further object is the incorporation, directly in the carbureter, of means for heating the liquid fuel so that, particularly in the case of the heavier hydrocarbons, such fuel will vaporize more readily when admixed with the air to form the charge. To the accomplishment of the foregoing and related ends, said invention, then, consists of the means herein-
after fully described and particularly pointed out in the claims.

The annexed drawing and the following description set forth in detail certain mechanism embodying the invention, such description closed means constituting, however, but one of various mechanical forms in which the principle of the invention may be used.

In said annexed drawing:—

Fig. 1 is a central vertical section of the carbureter; Fig. 2 is a transverse section thereof, taken on the plane indicated by the line 2—2, Fig. 1; Fig. 3 is a central vertical section of the lower portion of such carbureter, showing a modification in construction; and Fig. 4 is a broken side elevation of the carbureter on a smaller scale.

Referring first to the construction of the carbureter proper, the body of the device will be seen to consist of a tubular casing 1, preferably in the form of an elbow, provided with an air inlet opening 2 at approximately right angles to the outlet opening 3, which is connected, of course, to the engine manifold, as need not be further explained. The throttle consists of a butterfly valve

4 of the usual construction on a spindle 5 mounted in such outlet opening, and provided with suitable means for operating the same from the dash, in the case of an automobile, or elsewhere as most convenient. Of such operating means, the only parts shown (see Fig. 4) consist of a lever 6 secured to one end of the shaft 5 and a connecting rod 7 and leads from this lever to any desired point for the purpose of operation. The movement of such lever is limited by a stop 8 on the outside of the casing, when the valve is in closed position.

Rising centrally from the bottom of the casing is a fuel supply duct 10 in the upper end of which is fitted a nozzle 11. Such nozzle communicates with the interior of a vertically reciprocable weighted valve member 12 (see Fig. 1, the upper portion of which is slidable in a dash pot 13 supported centrally within the carbureter casing, by means of radial, spider-like arms 14. The lower portion of valve 12 is recessed at 15 to fit around the nozzle 11 and leading from the upper portion of such recess 15 are radial slots 16 through which the fuel as it escapes from the nozzle is adapted to be discharged into the annular space between the valve and the surrounding casing wall.

This space is designed to be filled by an annular valve seat 17, in the normal position of the parts last referred to, in which such central weighted valve occupies its lowermost position, and said annular valve seat member is disposed to close the lateral orifices 16 therein. This seat is beveled above and below, so that its inner face is of relatively narrow width, and it is adapted to be adjusted to occupy various positions vertically in the casing, by a pin 18 projecting through an inclined slot 19 in the wall of the case (see Fig. 4) to which a rod 20 is connected for the purpose of operation.

The lower portion of duct 10 is constricted and formed with an integral valve seat 21 adapted to co-operate with a valve 22 on the lower end of an elongated stem 23, the upper end of which is attached to the central weighted valve 12, such stem passing centrally through the nozzle 11 and having sufficient clearance to allow the fuel to escape into the radial slots 16 in such central valve, as previously described. Projecting from the valve 22 is a needle-like extension 24 adapted to project within the constricted

portion of the duct 10. This extension is tapered slightly from one end to the other, save for a short cylindrical section immediately adjacent the valve body, such cylindrical section being adapted to fit the constricted portion of the duct to entirely shut off the flow of fuel therethrough until the valve body has been raised a slight, predetermined distance. Thereupon the tapering portion of the valve extension acts directly as a needle valve, permitting an increase in flow of fuel as the valve is raised higher and higher.

Loosely surrounding the intermediate portion of the valve stem 23 and lying in the corresponding intermediate, enlarged portion of the fuel duct, is a cylindrical member 25, that is designed to rest of its own weight in the position shown, said member being formed to leave a slight clearance, not only between it and the conical bottom of the duct, but also between it and the side wall of such duct, through which clearance the fuel can pass from the supply connection 26, upon raising valve 22, to the nozzle 11. Such enlarged portion of the fuel duct is in turn surrounded by a casing 27, through which heated gases from the exhaust of the engine are designed to be passed in the direction indicated by the arrows, so as to maintain this portion of the duct at a relatively high temperature. The fuel, it will be observed, is caused to pass in a more or less thin film directly in contact with such heated wall, and so be heated to a point where its vaporization will be materially facilitated upon its being discharged in the upper portion of the carbureter.

In the construction illustrated in Fig. 1, the connection 26, through which fuel is supplied to duct 11, is directly attached to the latter, but the arrangement illustrated in Fig. 3 is preferable, consisting of a hollow sleeve 28 that is clamped between the bottom of the duct and a polygonal head 29 on the end of a tubular member 30, threaded in the lower portion of the duct. The construction is such, that, upon rotating the member 30, so as to slightly loosen the same in the casing, the sleeve 28 may be left in any desired position with respect to the casing. The member 30 serves the further purpose of providing an upwardly facing seat 31, upon which normally rests a weighted valve in the form of a plunger 32, having its lower end fitted to such seat, and its sides cut away to allow a relatively free passage of the fuel when the valve is raised. In order to insure such seating of this valve, the lower end of the extension 24 of the valve 22, that controls the fuel supply, is adapted to engage with a stop 33 resiliently supported in said plunger.

The operation of the carbureter may now be conveniently reviewed. Assuming the

position of the parts to be as in Fig. 1, it being understood that the annular valve seat 17 will be initially adjusted as desired within the range of the slot 19, the fuel supply is of course shut off by valve 22, as well as the air supply past the central weighted valve 12. Upon starting the engine, however, the suction, as regulated by the throttle valve 4, will immediately lift such air valve, and thus the supplemental fuel control valve, so as to respectively open the annular air passage and lift the supplemental valve sufficiently to permit a slight flow of fuel through the nozzle 11 and its discharge by way of the radial passages in the air valve 16. As the suction effect of the engine increases, it will lift the air valve higher and higher, and correspondingly raise the supplemental valve with its tapered extension, so as to admit an increasing amount of fuel.

The effect of raising the annular valve or valve seat 17 will obviously be to require the valve member 12 to be raised that much higher before the carbureter begins to function, with the result that a correspondingly richer mixture is produced, due to the fact that valve 22 controlling the fuel supply has been raised to a corresponding degree. It will be observed, however, that the adjustment of valve seat 17, which coöperates with said valve 12 to close the annular space between the nozzle and the surrounding casing wall, does not affect the normal position of said valve 12, nor of the fuel control valve 22. On the contrary, the latter remains seated at all times until the engine is actually started, and the suction of the engine raises the valve 12. This capacity for movement of the valve seat 17, wholly independent of valve 12, takes on particular significance where, as in the illustrated construction, no float valve for controlling the fuel supply is intended to be utilized.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

1. In a device of the character described, the combination of a tubular casing having an air inlet opening; a fuel supply duct with a nozzle rising centrally within said casing; an annular, vertically adjustable valve seat fitted within said casing; and a central, vertically reciprocable valve slidably fitting within said annular valve seat and adapted to be raised by the suction of the engine, said seat being adjustable without affecting the normal position of said valve and the latter being recessed in its under face to fit around said nozzle and having radial

discharge passages communicating with such recess.

2. In a device of the character described, the combination of a tubular casing having an air inlet opening; a fuel supply duct with a nozzle rising centrally within said casing; an annular, vertically reciprocable valve seat fitted within said casing; a central, vertically reciprocable valve slidably fitting within said annular valve seat and adapted to be raised by the suction of the engine, said seat being adjustable without affecting the normal position of said valve and the latter being recessed in its under face to fit around said nozzle and having radial discharge passages communicating with such recess; and a fuel-control valve attached to said valve.

3. In a device of the character described, the combination of a tubular casing having an air inlet opening; a fuel supply duct with a nozzle rising centrally within said casing, said duct having an orifice near its lower end; a vertically reciprocable valve fitted around such nozzle and adapted to be raised by the suction of the engine; a valve-member attached to said reciprocable valve and adapted to project through the orifice at the bottom of said duct; and a weighted valve in said duct below said valve-member normally actuated by gravity to close said duct, said valve-member being adapted to engage with said weighted valve to assist in holding the same closed.

35 4. In a device of the character described, the combination of a tubular casing having an air inlet opening; a fuel supply duct with a nozzle rising centrally within said casing, said duct having an orifice near its lower end; an annular, vertically adjustable valve seat fitted within said casing; a central vertically reciprocable valve fitted within said annular valve seat and adapted to be raised by the suction of the engine, said central valve being recessed in its under

45 face to fit around said nozzle and having radial discharge passages communicating

with such recess; a valve-member attached to said central valve and adapted to project through the orifice at the bottom of said duct; and a weighted valve in said duct below said valve-member normally actuated by gravity to close said duct, said valve-member being adapted to engage with said weighted valve to assist in holding the same closed.

5. In a device of the character described, the combination of a tubular casing having an air inlet opening; a fuel supply duct rising centrally within said casing; a chamber, connected with the engine exhaust, surrounding a portion of said duct; a valve and valve seat coöperating to substantially close the passage through said casing, said valve seat being externally adjustable and said valve being adapted to be raised by the suction of the engine; and a second valve connected to be operated by said first valve and adapted to control the supply of fuel through said duct from a point below said chamber.

6. In a device of the character described, the combination of a tubular casing having an air inlet opening; a fuel supply duct with a nozzle rising centrally within said casing, said duct having an intermediate enlarged portion and a valve seat near its lower end; a cylindrical member in such intermediate duct-portion leaving a slight clearance between the inner surface of the latter and said member; a chamber, connected with the engine exhaust, surrounding such duct-portion; a vertically reciprocable valve adapted to be raised by the suction of the engine; and a second valve adapted to coöperate with the seat at the bottom of said duct, said valve having a stem passing centrally through said member and attached to said first valve.
